[57] CLAIM

The ornamental design for a cabinet handle, as shown and described.

DESCRIPTION

FIG. 1 is a perspective view of a cabinet handle showing my new design;

FIG. 2 is an enlarged top view;

FIG. 3 is an enlarged side view;

FIG. 4 is an enlarged end view;

FIG. 5 is an enlarged bottom view; and,

FIG. 6 is an enlarged side view of a second embodiment of the design of FIG. 1, the only difference being the use of a transparent material for the cross member.

FIG. 1.

FIG. 2.

FIG. 3.

FIG. 4.

FIG. 5.

FIG. 6.
